UNITED STATES PATENT OFFICE.

WILEY S. WRIGHT, OF ST. LOUIS, MISSOURI.

IMPROVEMENT IN STOVES.

Specification forming part of Letters Patent No. 40,073, dated September 22, 1863.

To all whom it may concern:

Be it known that I, WILEY S. WRIGHT, of St. Louis, in the county of St. Louis and State of Missouri, have invented a new and useful Improvement in Sliding Doors for Stoves and Furnaces; and I do hereby declare that the following is a full, clear, and exact description thereof, reference being had to the accompanying drawings, making a part of this specification, in which—

Figure 1 is a front view of the front plate of a stove having my improved sliding doors applied to it. Fig. 2 is a view of the opposite side of Fig. 1, showing one of the doors in dotted lines thrown back. Fig. 3 is a vertical transverse section through the middle of Figs. 1 and 2. Fig. 4 is a perspective view of the inside of one of the sliding doors.

Similar letters of reference indicate corresponding parts in the several figures.

The object of my invention is to construct and apply sliding doors to stove and furnace plates in such manner that the doors will work with less friction than hitherto, at the same time they will not be affected in their perfect working by expansion and contraction, as will be hereinafter described.

To enable others skilled in the art to make and use my invention, I will proceed to describe its construction and operation,

The stove-plate A, to which the sliding doors B B' are applied, is, in the present instance, convex on its outer face, though it may be made flat or concave if desired. Along the bottom of this plate A a rounded bead or molding, a, is formed, which serves merely as an ornament or finish for the plate, but above the doors B B' is a hollow ogee molding, b, which is riveted to the plate A, and forms a groove of a peculiar character in which the upper projecting edge of the stove-doors slide, and by which they are retained in place.

The doors B B' may be made plain, or they may be ornamented in raised work, as shown in Figs. 1 and 3, and on the inside of each door, near the bottom of the vertical straight edge, I have formed a hook or finger, c, which hooks over and slides on the lower horizontal edge of the door plate or frame, as shown in Figs. 2 and 3. These hooks c are thus made to form inner bearings for the doors B B',

which hooks receive the weight of the doors when they are closed or partially closed, and while they thus support the inner ends of the doors they keep the lower edges of the doors in sufficiently close contact with the door-plate A for all practical purposes, and do away with nearly all friction, the bearing-surface of these hooks being so very small, thereby causing the door to slide with freedom and ease at all times, much more so than where the bottom of the door slides in a groove, as in stoves hitherto used. There being only one hook, c, on each door, and these hooks being arranged at or near the inner or vertical ends of the doors inside, it is necessary to support the outer ends when the doors are closed or partially closed, and for this purpose the projections e e on the outside face of the plate A, under the doors, are used, which projections are located at points directly under the outer ends of the doors when the latter are closed, and, being very narrow, these projections cause very little friction. These projections e e are notched to receive the lower edges of their respective doors before the ogee molding b is applied, and when this strip is secured in its place its lower edge projecting over the upper edges of the two doors, they are prevented thereby from being moved out of their places.

By this mode of applying sliding doors to their frames it will be seen that I obviate the objections to the grooves and other plans hitherto used, which cause the doors to bind and to work hard on account of expansion and contraction and friction.

My doors are supported upon the top edge of the lower part of the door-frame by narrow hooks or fingers, instead of in grooves formed in said frame, and neither ashes, cinders, nor anything else can offer obstructions to them.

The doors are moved back and forward by the thumb-pieces f f, and the stop-piece k, shown in Fig. 3, prevents either one of the doors from being moved too far forward, while the hooks c prevent the doors from being moved too far in the opposite direction.

The door-frame is notched at g g, as shown in Fig. 2, for the purpose of allowing the hooks c on the doors to enter these notches when the doors are opened. These notches allow

the doors to be opened to their full extent, and when thus opened they will be held by the hooks *c c* and outer supports, *e e*.

Having thus described my invention, what I claim as new, and desire to secure by Letters Patent, is—

1. Supporting the inner ends of sliding stove-doors upon the top edge of the lower part of the door-frame by means of hooks, which are applied to and move with the doors, substantially as described.

2. The outside auxiliary supports, *e e*, in combination with hooks *c c*, arranged on the

inside of the doors, substantially as and for the purposes described.

3. In combination with the inner hooks and outer supports, the overhanging strip *b*, applied to the door-frame, substantially as and for the purposes described.

Witness my hand in the matter of my application for Letters Patent on improved doors for stoves and ranges.

WILEY S. WRIGHT.
